SWIVEL CHAIR

Theodore R. Breed, Wichita, Kans.

Application January 3, 1956, Serial No. 39,575

Term of patent 14 years

(Cl. D15—1)

Fig. 1.

Fig. 3.

Fig. 2.

Fig. 1 is a top plan view of the frame portion of a swivel chair embodying my new design;

Fig. 2 is a front elevational view thereof; and

Fig. 3 is a side elevational view of the swivel chair.

The dominant features of my design reside in the portions shown in full lines, the sling seat element shown in broken lines in Fig. 3 being omitted from Figs. 1 and 2 for convenience of illustration only.

I claim:

The ornamental design for a swivel chair, substantially as shown and described.
